UNITED STATES PATENT OFFICE.

JOSEPH A. KIRCHGESSNER, OF BUFFALO, NEW YORK.

HOLDING DEVICE FOR EMBROIDERY WORK.

Application filed November 17, 1921. Serial No. 515,812.

To all whom it may concern:

Be it known that I, JOSEPH A. KIRCHGESSNER, a citizen of the United States, residing at Buffalo, in the county of Erie and State of New York, have invented certain new and useful Improvements in Holding Devices for Embroidery Work, of which the following is a specification.

My invention relates to a device for holding embroidery work, the embroidery material being held under proper tension by reason of its being clamped between the usual embroidery hoops so as to permit the ready passage of a needle through the material along the pattern stamped or otherwise marked thereon.

The primary object of my invention is the provision of a simple and practical device of this kind whereby any size of embroidery hoops may be easily retained in position so that the linen or other material stretched thereon can be conveniently worked upon with both hands free for manipulating the needle and thread.

Another object of my invention is to provide a device of this kind which can be attached to a table, to the arm of a chair, or to any other object, so that the embroidery work need not be held by the hand, which is commonly done and which results in the fingers of the person doing the embroidery becoming cramped, especially when using hoops of small size.

A further object of my invention is to provide a device of this class having an expandible and contractible hoop holder, a convenient support to which the hoop holder may be readily attached and from which it may be as easily removed, and simple means for attaching the support to a clamp, whereby the entire device may be secured to a table or other object.

The invention consists in the novel features of construction and in the arrangement and combination of parts to be hereinafter described and more particularly pointed out in the subjoined claims.

Referring to the drawings forming part hereof,—

Fig. 1 is a perspective view showing my improved device attached to a table top and having a pair of embroidery hoops attached thereto, with a piece of embroidery material stretched across the opening of said hoops.

Fig. 2 is a sectional elevation of the de-

vice as attached to a table top or other support.

Fig. 3 is a detached perspective view of one end of the expandible and contractible hoop holder or retainer, showing the two loops thereof arranged at right angles to each other, one loop being fastened to the end of said holder or retainer and the other being fastened to said last-mentioned loop.

Fig. 4 is a perspective view of a portion of the hoop holder or retainer along the region of the loops thereof and in the form in which it appears when supporting embroidery hoops.

Fig. 5 is a horizontal section through the complete hoop holder or retainer and the hoops supported thereby, taken on line 5—5, Fig. 2.

Fig. 6 is a detached perspective view of the support.

Fig. 7 is a vertical section taken on line 7—7, Fig. 2.

Fig. 8 is a cross section taken on line 8—8, Fig. 4, with the upper end of the support shown inserted into one of the loops of the hoop-holder or retainer.

While in the drawings I have shown the device attached to a horizontal table top or other object, with the result that parts thereof are either vertically or horizontally disposed, I desire it to be understood that the device may be attached to a vertically-disposed object, in which case the several parts of the device will be disposed at right angles to the positions shown in the drawings; or the device may be attached to an angularly-disposed object in which the parts of the device will be disposed obliquely to either a horizontal or a vertical plane. The exact disposition of the device is therefore a matter of choice, as it might be found more convenient by one person to place it in an angular position or even in a position in which the piece of embroidery is in a vertical plane; and for this reason, where in the specification the words "horizontal" or "horizontally" or the words "vertical" or "vertically" are employed, it is not applicant's intention to restrict himself to such positions, as these terms are employed only in the sense of describing positions or parts as they appear in the drawing, and the position of such parts will necessarily be changed when positioning the device otherwise than shown in the drawing.

Having reference more particularly to the

details of the device as illustrated; the numeral 11 designates a table top to which a clamp 12 is secured. This clamp may be of any suitable construction so far as that portion thereof relates whereby it is clamped to a table or other object. The particular clamp shown comprises an upper clamp member 14, a lower clamp member 15 spaced from said upper member and a connector member 16 connecting said upper and lower clamp members. The lower clamp member 15 has a clamping screw 17 threaded therethrough which is provided with a handle 18 for conveniently manipulating the same, and to the upper or inner end of said screw a clamping head 19 is rotatably mounted in the usual manner; said head being adapted to firmly engage the under side of the table top 11, or other object to which the clamp may be attached, thus drawing down the upper clamp member 14 against the upper side of the table top or other object. In order to prevent marring of the table top or other object, a felt pad 20 is applied to the under side of the upper clamp member.

Extending through the upper end of the clamp 12 and arranged parallel with the upper and lower clamp members 14, 15, respectively, is a slot 21, and formed through the upper wall of said slot and at right angles thereto is a transverse slot 22 having its walls beveled downwardly so as to gradually diminish the width of the same from the outer surface of said upper wall to the inner surface thereof. Secured at one end to the upper surface of said wall is a flat spring 23 having a V-shaped lock portion 24 which extends through the slot 22, for a purpose to appear hereinafter.

25 designates a support which is formed of a strip or bar of metal having an upright or body portion 26 which is bent at a right angle near one end thereof to form a foot 27 adapted to be entered in the slot 21 of the clamp, said foot having a transverse V-shaped depression 28, which is brought into registration with the transverse slot 22 in said clamp and is engaged by the pointed edge of the V-shaped lock portion 24 so that said support is securely locked to the clamp. The upright or body portion 26 is bent at a right angle at its upper end, as at 29, but in a direction opposite the foot 27 and the outer end of said bent portion 29 terminates in an upwardly-directed arm 30.

An expandible and contractible self-conforming and adjustable hoop-holder or retainer 31 is provided, which is formed of a narrow strip of spring material curved in the form of a ring and adapted to assume the shape of the hoops to be held thereby, whether said hoops are circular, as shown in full lines in Fig. 5; oval, as shown in dotted lines in said figure; or otherwise. The hoop

holder or retainer is self-conforming, for the reason that it is made of a narrow strip of spring material, and while normally circular or curved in the form of a ring, on account of its flexibility it is capable of assuming the shape of an oval hoop, or any other form of embroidery hoop now in use, and in applying it within the hoop it will conform to the exact formation of the latter. It is expandible or contractible, in a limited sense, owing to its flexibility. One end of said strip of spring material is soldered in a loop 32 and the strip is then curved into circular form with the other end thereof passed through said loop and, if desired, spaced a considerable distance from the loop so as to bring and retain an intermediate portion of the strip within the loop so arranged. The spring hoop-holder or retainer has a given diameter, which may be diminished by sliding the strip through said loop in one direction, and increased by sliding it in the opposite direction. The hoop holder is adjustable, in addition to being self-conforming, and expandible and contractible by reason of its construction and the employment of the loops arranged at one end of the strip forming the holder permits of enlarging or diminishing the size of the holder so that it may be used for holding a large number of sizes of embroidery hoops.

The free end of the strip forming said hoop-holder or retainer is preferably curved into the form of an eye, as at 33, so that when the strip is drawn in one direction or outwardly through the loop 32, said eye will come in contact with said loop and prevent withdrawal of the free end of said strip through the loop, thereby assuring a circular formation at all times, except when said holder or retainer is placed within embroidery hoops which are non-circular in shape.

Soldered or otherwise secured to the inner side of the loop 32, which may be referred to as a horizontal loop, is a second loop 34 arranged at a right angle to the loop 32, and which may be referred to as a vertical loop adapted to receive the upwardly-directed arm 30 of the support 25, the right-angled portion 29 of said support extending outwardly underneath the hoop-holder or retainer, as clearly shown in Fig. 2.

That portion of the hoop-holder or retainer between the loop 32 and the free end of the strip of material forming the same may be referred to as the surrounded portion of the holder or retainer, since a complete circle is formed by the strip of material from the end thereof secured to the loop 32 to that portion thereof entering the loop inside of the secured end thereof, as at 35, Fig. 4; that portion extending inwardly beyond the loop 32 and referred to as the surrounded portion, being utilized to in-

crease the diameter of the hoop-holder, if desired.

The hoop-holder or retainer is adapted to be fitted into the inner of two hoops 36, 37, 5 between which the embroidery material 38 is adapted to be clamped in the usual manner, said material as shown in Fig. 1 having any suitable pattern outlined thereon, according to which the material is to be embroidered.

Assuming the inner diameter of the inner hoop 34 to be four inches, the flexible strip forming the hoop-holder or retainer is adjusted so it will snugly fit within said inner 15 hoop and by grasping the strip at any convenient point outside of the loop 32 and pulling the surrounded portion of the strip outwardly, or by grasping the surrounded portion of the strip and particularly the eye 20 31 at the free end thereof and pushing the surrounded portion outwardly, the holder or retainer can be firmly fixed within the inner hoop so as to sustain both hoops and the material to be embroidered and clamped 25 therebetween. In this manner a substantial hoop-holder or retainer is provided which supports the hoop-clamped material in a manner that substantially the entire exposed and stretched area of the material is accessible 30 from both the top and bottom or, in other words, from opposite sides, and it will not be necessary by the use of this holding device to grasp the hoop with either hand. Thus, both hands are free for embroidering, 35 thereby assuring greater capacity and convenience and eliminating all possibility of the fingers or hands becoming cramped, due to holding the hoops in a fixed position, as is now necessary.

It is apparent, due to the flexibility of the strip of material from which the hoop-holder or retainer is formed, that it may be forced out of circular shape and assume an oval shape, as shown by dotted lines in Fig. 40 45 5, as some embroidery hoops are so formed, and as the tendency of the flexible strip forming the hoop-holder or retainer is always to assume a true circular formation, the strip will hold oval embroidery hoops in a 50 secure manner.

Having thus described my invention, what I claim is:—

1. A holding device for embroidery work, comprising a self-conforming expansible and contractible hoop-holder adapted to hold a pair of embroidery hoops having embroidery material clamped therebetween, and means for supporting said hoop-holder.

2. A holding device for embroidery work, comprising an expansible and contractible

hoop-holder which is adjustable and adapted to hold a pair of embroidery hoops having embroidery material stretched thereover and clamped therebetween, and means for supporting said hoop-holder in a manner to expose substantially the entire area of opposite sides of the stretched portion of said embroidery material.

3. A holding device for embroidery work, comprising an adjustable self-conforming ring capable of being varied in diameter to fit within embroidering hoops of different diameters, a clamp adapted to be secured to an object, and a support removably applied to said clamp and having said ring removably applied thereto.

4. In a device of the kind described, the combination with a pair of embroidery hoops fitting one within the other, of a holding device for said hoops comprising an expansible and contractible ring formed of a strip of spring material fitting within the inner of said embroidery hoops and having a loop secured to one end thereof and a portion thereof passed through and extended beyond said loop to permit of sliding a portion of said material back and forth through said loop to increase or diminish the diameter of said ring, and means for supporting said ring.

5. A holding device for embroidery work, comprising an expansible and contractible ring formed of a strip of flexible material having a loop secured to one end thereof and a portion thereof passed through and extended beyond said loop to permit of sliding a portion of said material back and forth through said loop to increase or diminish the diameter of said ring, a second loop secured to said first-mentioned loop and arranged at a right angle thereto, and a support having a portion thereof inserted into said second loop to support said ring.

6. A holding device for embroidery work, comprising an expansible and contractible ring adapted to be engaged with the inner surface of the inner of a pair of hoops having embroidery material stretched thereover and clamped therebetween, a loop secured to the inner side of said ring and arranged at an angle to the surface of the stretched portion of the embroidery material, a clamp adapted to be secured to a table or other object, and a support removably secured to said clamp and formed of a bar having one end bent at a right angle and terminating in an arm extending into said loop.

In testimony whereof I affix my signature.

JOSEPH A. KIRCHGESSNER.
